Atty.

UNITED STATES PATENT OFFICE

HART J. GOSLEE, OF CHICAGO, ILLINOIS

ARTIFICIAL TEETH

Application filed May 12, 1928. Serial No. 277,142.

This invention relates to improvements in artificial teeth and it consists of the matters hereinafter described and more particularly pointed out in the appended claims.

The primary object of the invention is to provide an artificial tooth structure adaptable for simulating incisors, canines, bicuspids and molars and which includes the provision of a substantially full porcelain tooth of modern anatomical outline and a metallic backing secured thereto in a manner to insure a maximum of strength in the tooth which is readily capable of withstanding masticatory stresses.

Another object of the invention is to provide an artificial tooth wherein the porcelain portion has a small round opening in its lingual surface and a definite marginal edge or shoulder to accommodate a metallic backing with an integral post disposed in the opening, the backing including lateral shoulders to abut with like parts on adjacent teeth so that the said shoulders provide means substantially invisible from the buccal and labial sides thereof for connecting adjacent teeth together in bridge formation.

Still another object of the invention is to provide a tooth having incisal ends and occlusal and full labial and buccal surfaces of porcelain and which when assembled with others will afford minimum gingival contact and large interproximal spaces thus presenting a more natural and esthetic appearance and being more sanitary in use.

These objects of the invention as well as others, together with the many advantages thereof will more fully appear as I proceed with my specification.

In the drawing:—

Fig. 1 is a vertical sectional view through an artificial bicuspid tooth embodying my invention, as taken on the line 1—1 of Fig. 2.

Fig. 2 is a view in elevation of the tooth shown in Fig. 1, as from the lingual surface thereof.

Fig. 3 is a view in side elevation of the porcelain body of the improved tooth.

Fig. 4 is a perspective view of the metallic backing associated with the tooth body shown in Fig. 3.

Fig. 5 is a horizontal sectional view

through the tooth as taken on the line 5—5 of Fig. 1.

Fig. 6 is a view in elevation of a plurality of teeth embodying my invention arranged in assembled pontic forming relation, as looked at from the buccal side thereof.

Referring now in detail to that embodiment of the invention illustrated in the accompanying drawing, the improved tooth which as shown herein simulates a bicuspid, includes a porcelain body 1 the front or buccal portion of which discloses a full face or crown. Said body is formed with a rearwardly facing vertical ledge or shoulder 2 at each side thereof which extends up over the top or gingival end of said body. On the rear or lingual side of the body, near the incisal end, is a horizontally disposed, upwardly facing ledge or shoulder 3 which terminates at each end in a short vertical shoulder 4 spaced from and opposed to the incisal ends of the shoulders 2, to there provide a short vertical channel 5 in each side of the tooth body. This shoulder arrangement provides on the rear or lingual side of the body, a depressed portion 6 which forms a seat for a metallic backing or base associated with the body. In said depressed seat portion 6 near the top thereof is a vertically disposed recess 7 the purpose of which will later appear.

8 indicates the metallic backing for the tooth body, preferably made of an alloy of hard gold or other precious metal unaffected by moisture when in use for its intended purpose. Said backing in this instance is of shell form and its vertical edge 9 is of such a contour as to snugly fit against the shoulder 2 of the tooth body while its bottom horizontal edge 10 is of such a contour as to snugly fit the horizontal shoulder 3 of the tooth body. At the top of said backing on the inner face thereof is provided a pin like post 11 adapted to snugly engage in the recess 7 of the tooth body and said post is preferably formed as an integral part of the backing. The lateral bottom portions of the backing as best shown in Fig. 4 have depending extensions 12—12, one at each side thereof, which when the backing is in place upon a porcelain tooth

body, engages in the recesses 5—5 at the incisal end of the tooth body.

Each extension 12 is slightly thicker than the depth of the associated recess 5 and its outer surface is extended upwardly beyond

5 the plane of the bottom edge 10 of the backing shell to form a vertically disposed flat faced

shoulder or abutment 13 as best shown in Fig.

10 4. In fixed bridge work the proper teeth to be embodied in the bridge are assembled side

by side with the shoulders or abutments in engagement and said shoulders are soldered or otherwise connected together from the lingual side of the teeth. Thus these shoul-

15 ders provide good bonding portions between

the teeth of relatively large area which are substantially invisible from the buccal and labial sides when the bridge is in actual use.

20 In bridge work such as disclosed in Fig. 6 the construction described has many advan-

tages in that both tooth and backing are con-

25 vex in every direction and present incisal ends and occlusal surfaces and full labial and buccal surfaces of porcelain together with a blunt

rounded edge of porcelain for contact with the mucosa in the edentulous spaces.

25 When one or more of said teeth are assem-

bled in bridge relation tooth and backing are such form and shape as will afford minimum

30 gingival contact and large interproximal spaces thus subscribing to the exacting

esthetic and sanitary requirement of an ideal

35 pontic in fixed bridge work. Again though the invention has been described as a pontic

arrangement it is equally applicable to the construction of dowel crowns in connection

with any root end coping.

40 It provides a tooth having full incisal end and partial lingual and full occlusal surfaces

of porcelain and a thin round edge of porce-

lain for direct contact with mucosa in eden-

45 tulous spaces. Furthermore the teeth require but a minimum amount of solder in assembly

and there is an avoidance of display of metal

45 from the labial or buccal sides thereof. It

permits the provision of the large inter-

proximal spaces as best shown in Fig. 6 as a

means for sanitation so that retention of food

50 particles and decomposition thereof which is

unsanitary is avoided.

55 While in describing the invention, I have referred in detail to the form, construction

and arrangement of the parts thereof, the

same is to be considered as merely illustrative

55 and not as limitations except as may be spe-

cifically set forth in the appended claims.

I claim as my invention:

1. An artificial tooth comprising a body

60 having a depressed seat portion on its lingual

side and a channel in each side of the body

from the incisal end thereof opening into said

65 depressed seat portion, said depressed seat

portion being provided with an opening in

its gingival end, a metallic body disposed

65 upon said depressed seat portion and having

an integral post at one end engaged in said opening and having extensions at its other end engaged in said channels, said extensions providing flat faced abutments for attachment to like abutments of adjacent teeth.

2. A metallic backing for an artificial tooth comprising a shell like body having a front edge and a bottom edge, a post integral with the top portion of the shell on the concave side thereof and extensions on the bottom of said shell at the front edges thereof having portions extending below said bottom edge and there providing flat abutments at each side of said backing.

In testimony whereof, I have hereunto set

80

my hand, this 5 day of May, 1928.

HART J. GOSLEE.
